UNITED STATES PATENT OFFICE.

ALBERT L. CRAMER, OF DENVER, COLORADO.

ARCH SUPPORT.

Application filed December 12, 1923. Serial No. 680,274.

To all whom it may concern:

Be it known that I, ALBERT L. CRAMER, a citizen of the United States, residing at Denver, in the county of Denver and State 5 of Colorado, have invented certain new and useful Improvements in an Arch Support, of which the following is a specification.

This invention relates to elastic foot bands and adjustable arch supports and particularly to those supporting the metatarsal bones of the foot. It consists of an elastic webbing shaped so as to conform to the foot. A pocket, secured to the lower side of the device and opening transversely with 10 the webbing is provided to receive one or more pads. As these pads which are preferably wedge-shaped extend towards the inner side of the foot, and are inserted in the pocket transversely of the foot they provide a firm but yieldable cushion for the instep or arch.

In the drawings:

Figure 1, represents a bottom plan view; Figure 2, a cross section, and 25 Figure 3, shows the application of the invention.

Referring more in detail to the drawing, the numeral 1 designates the elastic web of such width as to prevent binding and to confine the muscles of the arch or instep. The ends of the web are secured by a non-elastic fabric 2, which prevents the web from wrinkling or curling transversely and at the same time affords a firm gripping or seating of 30 the band on the upper side of the foot.

A pocket 3, is secured to the under side of the band being of the full width thereof and

of semi-circular design. The pocket is of firm or elastic material as the band whereby the walls of the pocket may be slightly 40 stretched or placed under tension upon insertion of the pads or fillers 4. The pads are substantially of corresponding shape and of tapering thickness being formed of cushioning material, such as felt. The free edge 45 of the pocket is turned inwardly and stitched, the inturned edge 5 forming a shoulder which serves to abut or overhang the adjacent pad for retaining the same in the pocket.

In use, the band is placed about the foot with the pocket opening toward the inside and the said pocket is then filled to the proper capacity with the felt cushion. Such an arrangement snugly fits the foot and gives 55 the wearer relief and comfort while on his feet.

What is claimed is:

An arch supporter comprising an elastic web, a nonelastic member secured to and connecting the ends thereof, a semicircular pocket of similar elastic web secured to the supporter opposite the connecting member, and cushioning fillers of substantially semicircular form adapted to be inserted in said 60 pocket, the straight side of the fillers being thicker than the curved edge, said pocket having its free edge turned inwardly for forming an internal shoulder to overhang the adjacent filler to assist in retaining the 65 same against displacement.

In testimony whereof I affix my signature.

ALBERT L. CRAMER.
